UNITED STATES PATENT OFFICE.

JOHN McCLELLAND, OF PHILADELPHIA, PENNSYLVANIA, ASSIGNOR OF ONE-HALF TO MICHAEL J. HUNT AND ONE-HALF TO I. CLIFFORD VAIDEN, BOTH OF PHILADELPHIA, PENNSYLVANIA.

CARBURETOR.

Application filed October 2, 1919. Serial No. 327,956.

To all whom it may concern:

Be it known that I, JOHN McCLELLAND, a citizen of the United States, residing at Philadelphia, in the county of Philadelphia and State of Pennsylvania, have invented certain new and useful Improvements in Carburetors, of which the following is a specification.

One object of my invention is to provide an improved carburetor which will thoroughly mix air with fuel, such for example as gasoline, prior to the entrance of the mixture to the cylinders of an internal combustion engine.

Another object of my invention is to provide improved means which will automatically operate to cause the admission of air into a carburetor so as to provide for the proper mixture of the air with the fuel.

A still further object is to make my invention of a simple and durable construction and so that it can be easily and quickly manipulated.

These objects, and other advantageous ends which will be described hereinafter, I attain in the following manner, reference being had to the accompanying drawings in which—

Figure 1 is an elevation of my improved carburetor showing certain of the parts in vertical central section,

Figure 2 is a transverse section taken on the line 2—2 of Figure 1, and

Figure 3 is a fragmentary section taken on the line 3—3 of Figure 2 showing my improved mixing fan.

Referring to the drawings, 4 represents the body portion of my improved carburetor which, in the present instance, is made in three sections, 5, 6 and 7. The section 6 is made hollow and is provided with two air chambers 8 and 9; there being a space 10 provided between two extensions 11 and 12 of the body section 6.

A mixing fan 13 has hollow blades 14 which extend at an angle and this fan is positioned within the space 15 of the section 7 space 15 serving as a mixing chamber. The interiors of the blades 14 communicate with a hollow head 16 and said blades extend from said hollow head, as clearly shown in Figure 2. Each of the blades adjacent its top edge is provided with a plurality of perforations 17. A hollow spindle tube

18 is rotatably mounted in a ball bearing 19; said ball bearing being preferably removable by screw threading the same as shown in Figure 1. The spindle tube 18 has a contracted neck 20 into which projects the upper open end 21 of a nozzle 22; 60 said nozzle extending upwardly from the section 5 and adapted to receive gasoline or other fuel which may be fed thereto by a pipe 23 from a fuel supply chamber which is open to atmospheric pressure. The interior of the spindle or tube 18 is larger than the nozzle 22 so that air from the chamber 9 can pass upwardly through the tube 18.

The extension 11 has an opening 24 and the extension 12 has an opening 25, both of 70 said openings communicating with the atmosphere. A rod 26 slidably extends through the extension 11 and through the opening 25 into the chamber 9. Valves 27 and 28 are secured to the rod 26 for the 75 purpose of normally closing the respective openings 24 and 25. A spring 30 is interposed between the top of the extension 11 and a nut 31 which is preferably screwed on the upper end of the rod 26. Thus the 80 spring 30 normally holds the valves 27 and 28 in positions respectively closing the openings 24 and 25.

The section 7 is adapted to be connected to the intake manifold of an internal combustion engine and the operation of the engine causes a suction to be produced in the chamber 15 due to the action of the engine in the usual manner. This suction causes fan 13 to rotate and valves 27 and 90 28 to open and admit air to chambers 8 and 9. The air admitted to chamber 8 goes between the blades of the fan to the mixing chamber. The air admitted to chamber 9 goes through tube 18 to the contracted neck 95 20 where it mingles with the gasoline coming from nozzle 21 and passes as a rich vapor into the fan which distributed the vapor in the mixing chamber. To secure the best results a materially larger quantity of 100 air should be fed to the mixing chamber through chamber 8 than can profitably be fed from chamber 9 through spindle 18 and the quantities fed through each path should at all times be properly proportioned. If a 105 greater or less quantity of air is drawn in through chamber 8, the quantity drawn in through chamber 9 should be increased or

decreased in the same ratio. For this reason opening 24 is made larger than opening 25 and valves 27 and 28 are connected so that, when the suction increases or decreases the 5 valves will open or close in like degree.

By providing a comparatively narrow neck 20 the fuel and the air in the tube 18 will mix to a certain extent prior to passing out through the perforations 17. By causing 10 this latter mentioned air and fuel to pass outwardly through the comparatively small perforations 17 and by the rotation of the fan within the space 15, the fuel and the air will be thoroughly mixed and will be in condition 15 to provide a powerful explosion when admitted into the cylinders of the engine.

It will thus be noted that the fan and its connected parts perform a number of operations. First it causes the mixture of the fuel 20 coming through the nozzle with the air coming through the tube. Second it causes the air and fuel mixture to pass out of comparatively small perforations and thereby distribute various quantities of mixed fuel 25 and air to be agitated by the rotation of the fan. By this means I secure a practically perfect mixture of the fuel and air in a condition which is readily explosive so as to provide great power.

By having the two valves 27 and 28, air 30 can be independently supplied to the chambers 8 and 9 and since a vacuum or partial vacuum is established due to the suction of the engine, the air will be drawn separately 35 through the passages 24 and 25 so that the rotation of the fan will not interfere with the suction of the fuel and air upwardly through the perforations in the fan blades. Thus, by the provision of the valves 27 and 40 28 the chambers 8 and 9 are independently supplied with air and when the device ceases acting, the valves will automatically operate to close the respective passages and prevent evaporation of the fuel and the entrance of 45 dirt into the chambers.

While I have described my invention as taking a particular form, it will be understood that the various parts of my invention 50 may be changed without departing from the spirit thereof, and hence I do not limit myself to the precise construction set forth, but consider that I am at liberty to make such changes and alterations as fairly come within the scope of the appended claims.

Having thus described my invention, 55 what I claim as new and desire to secure by Letters Patent is:—

1. A carburetor including a hollow body 60 forming a mixing chamber; a fan, mounted in the mixing chamber, having hollow blades provided with outlet openings; a rotatably mounted spindle carrying the fan and having a passage therethrough open at the lower end to receive air and communicating 65 at the other end with the interior of

the fan, and a fuel nozzle extending into the open end of the spindle but terminating short of the discharge end.

2. A carburetor including a hollow body 70 forming a mixing chamber; a fan, mounted in the mixing chamber, having hollow blades provided with outlet openings; a rotatably mounted spindle carrying the fan and having a passage therethrough open at the lower end to receive air and communicating at the other end with the interior of the fan; a fuel nozzle extending into the open end of the spindle; an air intake for admission of air to the spindle; an air intake for admitting air to the mixing chamber, and means 75 for controlling admission of air to the spindle and the mixing chamber.

3. A carburetor including a hollow body 80 forming a mixing chamber; a fan, mounted in the mixing chamber, having hollow blades provided with outlet openings; a rotatably mounted spindle carrying the fan and having a passage therethrough open at the lower end to receive air and communicating at the other end with the interior of the fan; a fuel nozzle extending into the open end of the spindle; an air intake for admission of air to the spindle; an air intake for admitting air to the mixing chamber, and common means for controlling admission of air to the spindle and the mixing 85 chamber.

4. A carburetor including a hollow body 90 forming a mixing chamber; a fan, mounted in the mixing chamber, having hollow blades provided with outlet openings; a rotatably mounted spindle carrying the fan and having a passage therethrough open at the lower end to receive air and communicating at the other end with the interior of the fan; a fuel nozzle extending into the open end of the spindle; an air intake for admission of air to the spindle; an air intake for admitting air to the mixing chamber, the opening of the latter intake being 95 the larger, and means for controlling admission of air to the spindle and the mixing chamber.

5. A carburetor including a hollow body 100 forming a mixing chamber; a fan, mounted in the mixing chamber, having hollow blades provided with outlet openings; a rotatably mounted spindle carrying the fan and having a passage therethrough open at the lower end to receive air and communicating at the other end with the interior of the fan; a fuel nozzle extending into the open end of the spindle; an air intake for admission of air to the spindle; an air intake for admitting air to the mixing chamber; a valve for controlling the admission 105 of air through each intake, and a connection between the valves whereby they open and close concurrently.

6. A carburetor including a hollow body 110

forming a mixing chamber; a fan, mounted in the mixing chamber, having hollow blades provided with outlet openings; a rotatably mounted spindle carrying the fan and having a passage therethrough open at the lower end to receive air and communicating at the other end with the interior of the fan; a fuel nozzle extending into the open end of the spindle; an air intake for admission of air to the spindle; an air intake for admitting air to the mixing chamber; a valve for controlling the admission of air through each intake; a connection between the valves whereby they open and close concurrently, and a spring normally holding the valves closed but permitting them to be opened by the suction due to operation of the engine and to move from or toward their closing position as the suction increases or decreases. 15 20

In testimony whereof I have signed my name to this specification.

JOHN McCLELLAND.
